DESIGN FOR A BLOUSE

Margaret K. Breslauer, New York, N. Y.

Application November 22, 1939, Serial No. 88,426

Term of patent 7 years

To all whom it may concern:

Be it known that I, Margaret K. Breslauer, a citizen of the United States, residing at New York city, county of New York, State of New York, have invented a new, original, and ornamental Design for a Blouse, of which the following is a specification, reference being had to the accompanying drawing, forming part thereof.

The single figure of the drawing is a view in front elevation of a blouse incorporating my new design.

The characteristic feature of my design resides in the panel extending around the neck opening at the front of the blouse, the remainder of the blouse being of conventional form.

I claim:

The ornamental design for a blouse, substantially as shown and described.

MARGARET K. BRESLAUER.
